UNITED STATES PATENT OFFICE

2,261,708

FEEDER FOR COUNTING MACHINES

Nelson S. Welk, Athens, Ohio, assignor to The
McBee Company, Athens, Ohio, a corporation
of Ohio

Application December 21, 1940, Serial No. 371,129

3 Claims. (Cl. 271—61)

My invention relates to that class of machines described in my copending divisional application Serial No. 352,703, of which this is a continuation in part.

The present case out of which Serial No. 352,703 was divided, described a machine for counting cards which is very successful in commercial practice. In that application I have shown a machine the frame of which has at its top two parallel shafts one at the top of each side of the frame and which extend longitudinally of the frame. A cross bar is slidably mounted on these rods. Means are provided to lock the cross bar in position when its proper location has been ascertained. This cross bar carries the magazine or card support. In practice it has been found that the two rods, upon which the cross bar slides interfere with the operator when he is placing a stack of cards in the magazine or card support in position to be fed into the machine in which they are to be counted.

The principal object of my invention is to improve the support for the stack of cards.

A further object is to entirely do away with the parallel rods or shafts without sacrificing the feature of a single movement for adjusting the card support.

My means of accomplishing the foregoing objects may be more readily understood by having reference to the accompanying drawings, which are hereunto annexed and made a part of this specification in which:

Fig. 1 is a top or plan view of the front portion of my counting machine;

Fig. 2 is a side elevation partly in section of a portion of the machine;

Fig. 3 is a detail view showing a side elevation of my improved support for the cards; and

Fig. 4 is a front elevation of the same.

Similar reference numerals refer to similar parts throughout the entire specification.

As shown in the drawings and described in the said copending applications the counting machine (only a fragmentary portion of which is shown in the drawings of this application) has a frame having sides 1 and 2 in which are mounted the ends of the various shafts which carry the rollers of the machine.

A main and feeding roll 3 is mounted on a shaft 4. This shaft also carries two card supporting rolls 5 and 6. Spacing plates 7 and 8 are mounted on a shaft 9 and are slidably mounted thereon to provide for lateral movement to adjust the plates 7 and 8 to cards of various widths.

As described in the said copending applications various sets of carrying rolls are provided to

carry the cards through the machine, but as this case relates solely to the magazine or card support specific details of said parts is omitted.

A table 10 is mounted in the front of the machine. This table 10 is provided with a longitudinal groove 11 in which is preferably mounted a channel 12 the edges of which are inturned forming flanges 13 and 14. The card support 15 is formed of an angular plate the base 16 of which is secured to a sliding block 16' by means of bolts 17 or in any other convenient manner.

This block 16' is formed with two grooves 18 and 19 which are fitted to the inturned flanges 13 and 14 and slideable thereon. A friction spring 20 is secured to the bottom of the block 16' by means of nuts 21 on the bolts 17. This spring 20 bears against the surface of the channel 12, and resists free movement of the block.

It will be clear from the foregoing description that the card support 15 can be moved forward or backwards in the channel 12 to accommodate various sizes of cards. The friction caused by the pressure of spring 20 on the channel 12 affords the only resistance which, while easily overcome by manual operation, is ample to hold the card support 15 in its proper location to support the cards which are to be counted.

Having described my invention what I regard as new and desire to secure by Letters Patent is:

1. In a card counting machine having a frame and feed rollers; comprising a table adjacent the main feed roller, said table having a groove therein, a channel member in said groove said channel member having inturned flanges, a block mounted and slideable on said inturned flanges, an angular card support carried by said block, a spring secured to said block adapted to cause frictional resistance to the longitudinal movement of said block.

2. In a card counting machine having a frame and feed rollers, comprising a table adjacent the main feed roller, said table having a groove therein, a channel member in said groove, a block mounted and slideable in said channel member, an angular card support carried by said block means to cause frictional resistance to the movement of said block.

3. In a card counting machine having a frame and feed rollers, comprising a table adjacent the main feed roller, said table having a groove therein, a channel member in said groove, said channel member having inturned flanges, a block mounted and slideable beneath on said inturned flanges, an angular card support carried by said block, means to cause frictional resistance to the longitudinal movement of said block.

NELSON S. WELK.
